UNITED STATES PATENT OFFICE.

WALTER H. BODURTHA, OF DELAWARE, OHIO, ASSIGNOR TO SUNRAY STOVE COMPANY,
OF DELAWARE, OHIO.

DESIGN FOR A GAS RANGE.

Application filed December 30, 1925. Serial No. 15,901. Term of patent 3½ years.

To all whom it may concern:

Be it known that I, WALTER H. BODURTHA, a citizen of the United States, residing at Delaware, county of Delaware, and State of Ohio, have invented a new, original, and ornamental Design for Gas Ranges, of which the following is a specification, reference being had to the accompanying drawing, forming part thereof.

The figure is a perspective view of a gas range, showing my new design.

I claim:

The ornamental design for a gas range, as shown.

WALTER H. BODURTHA.
